Fig.10.

UNITED STATES PATENT OFFICE.

JARRET L. CAMERON, OF ORANGE, TEXAS.

OIL-WELL SEAL.

Application filed July 16, 1923. Serial No. 651,865.

To all whom it may concern:

Be it known that I, JARRET L. CAMERON, a citizen of the United States, residing at Orange, in the county of Orange and State of Texas, have invented certain new and useful Improvements in Oil-Well Seals, of which the following is a specification, reference being had to the accompanying drawings.

- 10 This invention relates to oil well seals and more particularly for a seal of the type used in wells drilled by the rotary process for stopping off the large casing of the well to the smaller casing.
- 15 In the drilling of oil wells by the rotary process it is customary to seat the large casing which is employed initially in the last strata of firm gumbo or hard formation, the well being drilled down from this
- 20 formation to the oil-sand by a smaller drill, a small size casing being inserted in the opening formed by this smaller drill. It is accordingly necessary to seal this small casing to the large casing above it. In performing
- 25 this operation it is necessary that a seal be employed which for the greatest efficiency in sealing must, when in position, be spaced from the adjacent wall of the casing so as to provide a clearance between its surface
- 30 and the adjacent surface of the large casing, so that the well may be washed and dirt and mud forced from about the screen at the lower end of the smaller casing may pass upwardly about the smaller casing through
- 35 the space between the seal and the adjacent face of the large casing and so from the well. For this purpose a space of approximately $\frac{3}{16}$ " clearance about the seal is desirable. It will, accordingly be obvious that a consider-
- 40 able expansion of the seal is necessary for proper engagement between the seal and large casing. It will furthermore be obvious that some means must be provided for introducing water through the seal and
- 45 under pressure to the lower casing so that this water may wash the dirt from about the screen of the smaller casing. Such seals usually employ a longitudinally shiftable member, which by its shifting expands a
- 50 resilient member against the walls of the larger casing. In order to accomplish this what is known as the setting tool is em- ployed.

An important object of this invention is to provide a setting tool affording means

for sealing the upper end of the seal and means for directing water through the seal.

A further object of the invention is to improve the general construction of the seal, to provide a device which is simple and durable in its construction, readily operated and which will be a general improvement in the art.

These and other objects I attain by the construction shown in the accompanying drawings, wherein for the purpose of illustration is shown a preferred embodiment of my invention and wherein:—

Figure 1 is a sectional view through a well casing showing a seal constructed in accordance with my invention positioned therein and as it appears when first lowered in the well;

Figure 2 is a similar view showing the setting tool disengaged and elevated preparatory to sealing operation;

Figure 3 is a view showing the sealing operation completed;

Figure 4 is a longitudinal sectional view taken through the setting tool and seal as combined;

Figure 5 is a side elevation of the stationary member of the seal, the locking ring being shown in position thereon in dotted lines;

Figure 6 is a detached sectional view through the bowl of the movable sleeve;

Figure 7 is a section on the line 7—7 of Figure 6;

Figure 8 is a section on the line 8—8 of Figure 4;

Figure 9 is an enlarged side elevation partially in section of the setting tool;

Figure 10 is an enlarged sectional view on the line 10—10 of Figure 4; and

Figure 11 is a section taken through the dogs of the setting tool showing the same expanded.

The seal proper comprises a stationary sleeve 10, a vertically movable sleeve 11, a locking device 12 for the vertical sleeve to lock the same in position upon the stationary sleeve, a locking device 13 for locking the stationary sleeve to the large casing C, an expandible packing element 14, a locking device 13^a for the expandible packing and means 15 for normally holding the movable sleeve against movement with relation to the stationary sleeve. The stationary sleeve 10 is threaded at its lower end, as indicated

105

110

at 16. Spaced from this threaded portion the sleeve is provided with an upwardly tapering enlargement 17, the spacing providing a wrench receiving portion 18 to which a wrench may be applied to fasten the lower end of the stationary sleeve into the smaller casing C' of the well. At the lower end of this tapered portion an outstanding flange 19 is formed providing an upwardly facing shoulder 20. Above the tapered portion a portion of the length of the stationary sleeve is provided with ratchet screw threads, as indicated at 21. The upper end of the stationary sleeve is interiorly screw-threaded with left-hand screw threads, as indicated at 22. Immediately below the interior screw threads the stationary sleeve has formed therethrough a plurality of circumferentially spaced threaded openings 23, the purpose of which will presently appear.

The movable sleeve 11 comprises a bowl section 24 and a sleeve extension 25 for the bowl section, the upper end of the bowl section being interiorly screw-threaded, as at 26, for coaction with the screw-threaded exterior of the lower end 27 of the extension 25. Through the threaded portions of the bowl and extension 25 are formed coacting threaded apertures 28 and 29, corresponding in number and arrangement to the openings 23 of the stationary sleeve 10 and coacting therewith to receive the locking elements 15, hereinbefore referred to. These locking elements preferably consist of threaded screws of brass or some similar material which may be readily sheared. The bore 30 of the lower end of the bowl is such that it has a sliding fit with the upper end of the stationary sleeve 10 and the bore of the extension 25 likewise has a sliding fit with this stationary sleeve. The bore of the bowl tapers upwardly from its lower end, as indicated at 31, and when positioned about the sleeve this taper of the bore forms a housing for the locking member 12 between the walls of the bowl and the adjacent face of the stationary sleeve. This locking member 12 consists of a split ring having a straight inner wall and a downwardly tapering outer wall, the ring being provided upon this inner wall with ratchet screw threads 32 coacting with the ratchet threads 21 of the stationary sleeve 10. The upper end of this ring during downward movement of the movable sleeve 11 is abutted by the lower end of the extension 25 and this ring is accordingly moved downwardly, expanding to permit its passage over the ratchet threads 21 of the stationary sleeve. After moving downwardly any upward movement of the ratchet sleeve is prevented by reason of the fact that the tapered walls of the bowl engaging against the tapered face of the split ring will force the threads 22 of this ring into engagement with the threads 21 of the stationary sleeve, pre-

venting upward movement of the locking ring 12 and accordingly upward movement of the bowl and extension forming the movable sleeve 11.

The lower end of the bowl is provided with a downwardly tapering portion 33 similar to the tapered portion 17 of the enlargement of the stationary sleeve 10, the upper end of this tapered portion terminating in an outstanding shoulder 34. The locking rings 13 and 13^a each have a straight outer wall provided with upwardly directed ratchet screw threads 35 and an inner wall having a taper corresponding to the tapers 33 and 17. These locking rings are provided with a lapped split joint, indicated at 36, and accordingly are expandable. The packing member 14 preferably consists of a cylindrical sleeve of fabric reinforced rubber. In assembling the device the ring 13 is first seated upon the taper 17, the packing element 14 is then applied in position and the ring 13^a seated upon the upper end of the packing device, the bowl 24 is then placed in position with its tapered end 33 downwardly and the locking ring 12 inserted in the bowl. The extension 25 is then placed in position in the upper end of the bowl and the screws or locking elements 15 directed through the bowl extension and the upper end of the stationary sleeve. In this position it will be seen that the movable sleeve is held against downward movement but that downward movement may occur at any time after the locking elements 15 are sheared. When these locking elements are sheared, if the movable sleeve is forced downwardly by any exterior force, when moved downwardly it will be locked against return movement by the locking member 12. During this downward movement the shoulder 34 by its engagement against the upper end of the uppermost locking ring 13^a will move this locking ring downwardly forcing the packing element 14 and lower locking element 13 downwardly likewise. When the lower locking ring reaches the lower limit of its movement it is expanded so that it is forced solidly into engagement with the casing C, compression of the packing element takes place to cause this packing element to swell outwardly and likewise engage against the wall of the casing to form a seal between the wall of the casing and the stationary sleeve 10. This compression likewise expands the uppermost locking ring 13^a and its threads will be forced into engagement with the casing C. It will be seen that the locking rings 13 and 13^a when forcibly expanded and engaged against the wall of the casing will be held against return movement by reason of the fact that the ratchet threads thereof will bite into the walls of the casing. These rings being lap-jointed will of themselves

serve to a certain extent as a seal, the true seal, however, being completed by the packing element 14.

The setting tool comprises a head 37 having a diameter such that it is rotatable within the extension 25 the upper end of the head being enlarged to form a downwardly extending shoulder 38 to abut the upper end of the extension 25 and limit the downward movement of the head in the extension. The upper end of the head is provided with a threaded socket 39 for the reception of the lower end of a drill pipe P. The lower end of the head is provided with a reduced tubular extension 40, the lower end of which is interiorly and exteriorly screw-threaded. The bore 41 of the tubular extension extends through the head 37 and communicates with the socket 39. The lower end of the head about the tubular extension is cupped to form a depending marginal flange 42. The exterior threads of the lower end of the extension are engaged by a collar 43, the upper end of which is cupped to provide an upwardly directed marginal flange 44. The lower end of the collar is exteriorly screw-threaded with left-hand screw threads for coaction with the left-hand screw threads 22 formed upon the interior of the upper end of the stationary sleeve 10. The numeral 45 designates a dog retainer comprising a member having a bore rotatably receiving the tubular extension 40 of the head 37. The external diameter of this member is the same as the external diameter of the head, as regards its central portion. The end portions of the member are reduced in diameter, as at 46, so that they will be rotatable within the cup portions of the head 37 and collar 44. This member is provided with longitudinally extending slots 47 housing dogs 48. Each dog 48 comprises a body portion 49 of a length equal to the distance between the adjacent faces of the marginal flanges 42 and 44 of the head and collar, the body portion being provided at its upper end with an extension flange 50 slightly less in thickness than the distance between the base of the groove 47 and the adjacent face of the flange 42 and at its lower end with a flange 51 which is much thinner. The under surface of the dog is recessed, as at 52, to provide a housing for a flat spring 56 which urges the dog outwardly in the groove. It will be seen that the dog when unrestricted will assume a position similar to that illustrated in Figure 9 at its lower end by reason of the reduced size of the flange 51 thereof being forced outwardly beyond the surface of the dog retainer and collar 43. The inner threads of the tubular extension 40 are adapted for engagement with a wash pipe P'.

It will be noted from an inspection of Figure 4 that when the setting tool is in posi-

tion within the extension the dogs are held in withdrawn position. With the parts in the position shown in this figure and with the lower end of the stationary sleeve connected to the smaller casing, the device is lowered into the well until the smaller casing C' is properly seated at which time the packing element 14 will be opposed to the large casing C adjacent the lower end thereof. The well is then washed by introducing water under pressure through the drill pipe P, which water passes through the bore 41 of the extension to the wash pipe P' to act upon the screen of the well, (not herein shown). After the washing of the well is completed the setting tool is released from the stationary sleeve without disturbing the engagement of the stationary sleeve with the casing C'. It is here pointed out that this rotation is more readily accomplished by reason of the fact that the dog holder 45 is rotatably mounted upon the setting tool. It is often the case that in washing a well dirt and sand will accumulate about the setting tool rendering rotation thereof extremely difficult. With the construction hereinbefore described rotation of the major portion of the setting tool is entirely unnecessary. After the release has been accomplished the setting tool is drawn upwardly by the use of the drill pipe. By this upward movement the dogs are released and forced outwardly by their springs so that they assume a position whereupon lowering of the setting tool their lower ends will come into engagement with the upper end of the extension 25. The setting tool is then dropped or otherwise brought into forcible engagement with the upper end of the extension 25, the engagement being accomplished by the expanded dogs. This forcible engagement will cause the locking pins 15 to be sheared, permitting the movable sleeve 11 to move downwardly to compress the packing and expand the locking rings in the manner hereinbefore set forth.

It will be obvious that by the use of apparatus constructed in accordance with my invention all of the necessary operations in the sealing of the well may be accomplished by a single structure and that a permanent seal is afforded by this structure. It will furthermore be obvious that the construction hereinbefore set forth is capable of considerable change and modification without in any manner departing from the spirit of my invention and I accordingly do not limit myself to such specific structure except as hereinafter claimed.

I claim:

1. An oil well seal comprising a stationary sleeve, a movable sleeve mounted on the sta-

- tionary sleeve, frangible means normally preventing movement of the movable sleeve, a packer carried by said stationary sleeve, means shiftable with the movable sleeve in one direction and locking the movable sleeve against movement with relation to the stationary sleeve in the opposite direction, members carried by the stationary and movable sleeves engaging opposite ends of said packer to compress the same during movement of the movable sleeve in the first named direction and means at opposite ends of the packer expanded during compression of the packer for engagement with the casing to engage the casing and maintain the packer in compressed position.
2. An oil well seal comprising a stationary sleeve, a movable sleeve mounted on the stationary sleeve, frangible means normally preventing movement of the movable sleeve, a packer carried by said stationary sleeve, means shiftable with the movable sleeve in one direction and locking the movable sleeve against movement with relation to the stationary sleeve in the opposite direction, members carried by the stationary and movable sleeves engaging opposite ends of said packer to compress the same during movement of the movable sleeve in the first named direction, said members comprising split rings having ratchet teeth upon their outer surfaces and engaging tapered portions of said stationary and movable sleeves.
3. An oil well seal comprising a stationary sleeve, a movable sleeve mounted on the stationary sleeve, frangible means normally preventing movement of the movable sleeve, a packer carried by said stationary sleeve, means shiftable with the movable sleeve in one direction and locking the movable sleeve against movement with relation to the stationary sleeve in the opposite direction, members carried by the stationary and movable sleeves engaging opposite ends of said packer to compress the same during movement of the movable sleeve in the first named direction, and means engaging the upper end of the stationary sleeve for supporting the stationary sleeve during lowering thereof into the well, said means providing a bore permitting the introduction of fluid therethrough to the stationary sleeve, said means being disengageable from the stationary sleeve and when disengaged vertically movable with relation thereto and expansible dogs carried by said means for expanding upon elevation thereof above the upper end of the movable sleeve to engage against the upper end of the movable sleeve to force the same downwardly.
4. An oil well seal comprising a stationary sleeve having ratchet screw threads, a movable sleeve mounted on the stationary sleeve, frangible means normally preventing movement of the movable sleeve, a packer carried by said stationary sleeve, means shiftable with the movable sleeve in one direction and locking the movable sleeve against return movement with relation to the stationary sleeve, comprising a split ratchet ring for coaction with the ratchet threads of the stationary sleeve housed within in a recess formed in said movable sleeve, and members carried by said stationary and movable sleeves engaging opposite ends of said packer to compress the same during movement of the movable sleeve in said direction.
5. An oil well seal comprising a stationary sleeve having ratchet screw threads, a movable sleeve mounted on the stationary sleeve, frangible means normally preventing movement of the movable sleeve, a packer carried by said stationary sleeve, means shiftable with the movable sleeve in one direction and locking the movable sleeve against return movement with relation to the stationary sleeve, comprising a split ratchet ring for coaction with the ratchet threads of the stationary sleeve housed within in a recess formed in said movable sleeve, and members carried by said stationary and movable sleeves engaging opposite ends of said packer to compress the same during movement of the movable sleeve in said direction, movement of the movable sleeve in said direction expanding said members for engagement with the casing to thereby prevent expansive movement of the packer after compression thereof.
6. In an oil well seal, a stationary sleeve adapted at its lower end for connection with the well casing and screw-threaded at its upper end, a second sleeve shiftable longitudinally of the stationary sleeve, a packer compressed by movement of the second sleeve and mounted upon the stationary sleeve, a dog carrier disposed within the second sleeve having dogs expanding upon withdrawal of the carrier from the sleeve to prevent return of the carrier to the sleeve, and a support for the seal rotatably directed through the dog carrier and engaged with the threads of the stationary sleeve.
7. In an oil well seal, a stationary sleeve adapted at its lower end for connection with the well casing and screw-threaded at its upper end, a second sleeve shiftable longitudinally of the stationary sleeve, a packer compressed by movement of the second sleeve and mounted upon the stationary sleeve, a dog carrier disposed within the second sleeve having dogs expanding upon withdrawal of the carrier from the sleeve to prevent return of the carrier to the sleeve, and a support for the seal rotatably directed through the dog carrier and engaged with the threads of the stationary sleeve, said support including a part limiting the expansion of the dogs of said carrier.

8. An oil well seal comprising a stationary sleeve adapted at its lower end for connection with the well casing and screw-threaded at its upper end, a second sleeve shiftable longitudinally of the stationary sleeve, a packer carried by the stationary sleeve and compressed by movement of the second sleeve upon the stationary sleeve, a dog carrier disposed within the second sleeve comprising a cylindrical member provided in its periphery with longitudinally extending slots, dogs disposed within said slots, springs locked by the base of the slots and the dogs for forcing the dogs outwardly, and a support for the seal rotatably directed through the dog carrier and engaged with the threads of the stationary sleeve.

9. An oil well seal comprising a stationary sleeve adapted at its lower end for connection with the well casing and screw-threaded at its upper end, a second sleeve shiftable longitudinally of the stationary sleeve, a packer carried by the stationary sleeve and compressed by movement of the second sleeve upon the stationary sleeve, a dog carrier disposed within the second sleeve comprising a cylindrical member provided in its periphery with longitudinally extending slots, dogs disposed within said slots, springs locked by the base of the slots and the dogs for forcing the dogs outwardly, and a support for the seal rotatably directed through the dog carrier and engaged with the threads of the stationary sleeve.

10. An oil well seal comprising a stationary sleeve adapted at its lower end for connection with the well casing and screw-threaded at its upper end, a second sleeve shiftable longitudinally of the stationary sleeve, a packer carried by the stationary sleeve and compressed by movement of the second sleeve upon the stationary sleeve, a dog carrier disposed within the second sleeve comprising a cylindrical member provided in its periphery with longitudinally extending slots, dogs disposed within said slots, springs locked by the base of the slots and the dogs for forcing the dogs outwardly, and a support for the seal rotatably directed through the dog carrier and engaged with the threads of the stationary sleeve.

15. An oil well seal comprising a stationary sleeve adapted at its lower end for connection with the well casing and screw-threaded at its upper end, a second sleeve shiftable longitudinally of the stationary sleeve, a packer carried by the stationary sleeve and compressed by movement of the second sleeve upon the stationary sleeve, a dog carrier disposed within the second sleeve comprising a cylindrical member provided in its periphery with longitudinally extending slots, dogs disposed within said slots, springs locked by the base of the slots and the dogs for forcing the dogs outwardly, and a support for the seal rotatably directed through the dog carrier and engaged with the threads of the stationary sleeve.

20. An oil well seal comprising a stationary sleeve adapted at its lower end for connection with the well casing and screw-threaded at its upper end, a second sleeve shiftable longitudinally of the stationary sleeve, a packer carried by the stationary sleeve and compressed by movement of the second sleeve upon the stationary sleeve, a dog carrier disposed within the second sleeve comprising a cylindrical member provided in its periphery with longitudinally extending slots, dogs disposed within said slots, springs locked by the base of the slots and the dogs for forcing the dogs outwardly, and a support for the seal rotatably directed through the dog carrier and engaged with the threads of the stationary sleeve.

In testimony whereof I hereunto affix my signature.

JARRET L. CAMERON.
